UNITED STATES PATENT OFFICE

DAVENPORT LAWSON, OF ELK, CALIFORNIA, ASSIGNOR TO GOODYEAR REDWOOD CO.,
OF ELK, CALIFORNIA, A CORPORATION OF MAINE

LOGGING SYSTEM

Application filed July 24, 1926. Serial No. 124,570.

This invention relates generally to systems or apparatus for conveying articles and has specific application in logging operations.

In the lumber industry it is customary 5 practice to use some form of device for conveying the logs from the timber area to a point where they may either be cut into timber or loaded on cars for transportation. It is preferable that this be done with some 10 form of apparatus which will lift the logs clear of the ground, since logs which are dragged are apt to be injured by splintering, or may gather rocks and gravel, thus making them difficult to run thru the mill. One 15 form of apparatus for accomplishing this result is shown in my Patent No. 1,394,745, issued October 25, 1921. This apparatus employs a system of cables supporting a traversing hoist carriage. The cables may be anchored to convenient spar trees and the movement of the carriage controlled from a remote yarder or donkey. This apparatus however is limited in its application since 20 only a comparatively small area may be covered after which operations must be suspended until the anchoring for the cables may be shifted. This obviously results in considerable waste of time and effort.

It is an object of this invention to devise a 25 logging system in which a comparatively large area may be covered before shifting of the apparatus.

It is a further object of this invention to 30 devise a logging system in which the hoisting carriage for driving and lifting the logs is movable in two directions to cover a relatively large area.

It is a further object of this invention to 35 devise an improved system for logging in which a hoist carriage is controlled by an arrangement of cables from a yarder in such a manner that it may be moved to any point above a large area.

It is a further object of this invention to 40 improve generally the construction of yarders suitable for use with the above system. It is proposed to provide means for readily fixing the position of the yarder with respect to a railroad track.

45 It is another object of this invention to de-

vise a special form of lead carriage suitable for use with the above system.

Further objects of this invention will appear from the following description in which I have set forth the preferred embodiment 55 of my invention. It is to be understood that although only one modification has been described and illustrated, the invention is capable of assuming a variety of forms within the scope of the appended claims.

50 Referring to the drawings:

Figure 1 is a perspective view showing the system in operation in a canyon or valley from which timber is being removed.

Fig. 2 is a plan view showing diagrammatically the system of this invention.

Fig. 3 is a side elevation of the yarder for controlling the cables.

Fig. 4 is a detail showing the manner in which the track rails are cut away for permitting the yarder frame to be supported directly by the track ties.

Fig. 5 is an end view of the yarder frame and truck showing the frame being supported by the truck.

Fig. 6 is a view similar to Fig. 5 showing the yarder frame being supported directly by the track ties.

Fig. 7 is a plan view showing the construction of the lead carriage.

Fig. 8 is a side elevational view showing the construction of the lead carriage.

Fig. 9 is a plan view showing the construction of the tail carriage.

Fig. 10 illustrates the use of the improved 85 anchoring plate for anchoring a block to a spar tree.

The system comprises generally an arrangement of cables which may be readily installed and put into operation over an area 90 from which the timber has been cut. These cables include tracking cables which extend upon opposite sides of the area, and a hoist line which spans the area and engages respectively at its ends lead and tail carriages 95 which are adapted to traverse the tracking cables. By moving the lead and tail carriages upon the tracking cables the hoist line may be moved above any point of the timber area to enable the hoist carriage to lift logs 100

and deposit the same upon a railroad car or other means of transportation.

Referring to Fig. 1 of the drawing, the system comprises generally an arrangement of cables designated generally at 10 and 11 which are normally positioned upon opposite sides of the area from which it is desired to remove logs, the cables being controlled by a plurality of winding drums located on the yarder 12. Certain of the cables 10 and 11 serve as a track for the traversing carriages 13 and 14 between which extends the hoist line 16. A hoist carriage 17 is supported by the hoist line 16 and is provided with a sling 18 or other suitable means for engaging logs 19. By selectively controlling operation of the winding drums of the yarder 12 the hoist carriage 17 may be moved back and forth upon the hoist line 16 or the carriages 13 and 14 may be moved to shift the hoist line 16 laterally so that the hoist carriage may be moved to any point above the area. The logs may be loaded upon cars 20 which may be run upon the track 21, a short spur track 22 being constructed for positioning of the yarder.

Referring now to Fig. 2 for a more detailed description of the system, the cables have been shown as anchored to the main spar trees 26 and 27 located upon the lead side of the area, and spar trees 28 and 29 located upon the tail side. For tracking the lead carriage 13 there is provided a pair of cables 30 and 31 which may be formed of a continuous cable entrained about block 33 secured to spar tree 27 and extending through cable shoes 32 secured to spar tree 26, the ends of the cables being made fast to suitable tail holds or stumps 32^a after obtaining the proper tension. Similarly the tail carriage 14 may be tracked upon cables 34 and 35 entrained about block 37 secured to spar tree 29 and extended through shoes 36 secured to spar tree 29, the ends being anchored to stumps 36^a. For effecting movement of the lead carriage 13 in either direction upon the tracking cables, there is provided what may be termed moving lines or cables 39 and 40, controlled by the winding drums 41 and 42 respectively of the yarder. A convenient arrangement for the moving line 39 is to anchor one end to a spar tree 43 or other suitable means adjacent the main spar tree 26 and to entrain the same about the block 44 secured to the carriage 13 and the block 45 anchored to the tree 26. The end of the line 40 may be anchored to a tree 46 located adjacent the tree 27 and may be entrained about a block 47 secured to the carriage 13, a stationary block 48 anchored to the tree 27, and the block 49 anchored to the tree 26. The line 40 may similarly be anchored at its end to the tree 27 and may be entrained over the moving block 47 secured to the carriage 13, and about the stationary blocks 48 and 49 se-

cured respectively to the trees 27 and 26. Similarly the tail carriage 14 may be controlled by means of moving lines 51 and 52 which are controlled from the winding drums 53 and 54 respectively. The line 51 may be anchored at its end to tree 55 and entrained over block 56 secured to the carriage 14, and block 57 anchored to the tree 28 to drum 53 of the yarder. The line 52 is likewise anchored at its end to tree 58 and is entrained over a moving pulley 59 secured to the carriage 14 and over stationary blocks 60 and 61 anchored to the trees 29 and 28 respectively, then to drum 54. It is obvious from the above that by winding the drum 41 and unwinding the drum 42 the lead carriage 13 may be moved from right to left, while by winding the drum 42 and unwinding the drum 41 the carriage is moved from left to right. Similarly winding up of the drum 53 and unwinding of drum 54 will cause the tail carriage 14 to move from right to left while conversely winding of the drum 54 and unwinding of drum 53 will cause the tail carriage to move from left to right.

The hoist line 60 is strung between the lead and tail carriages 13 and 14, and preferably has both of its ends entrained about the winding drums 61 and 62. For example, the hoist line is entrained about a single block 63 secured to the carriage 14 and about a pair of lead blocks 64 secured to the lead carriage 13 (see Figure 8). The block 65 may also be provided for guiding the hoist line to a point adjacent the spar tree 26. The hoist carriage 17 is provided with a plurality of sheaves 66 to permit free movement along the hoist line 60. In order to move the hoist carriage back and forth along the hoist line there is provided a main haul line or cable 67 controlled by the winding drum 68, and a haul back line 69 controlled by the winding drum 70. The main haul line 67 is secured to the hoist carriage 17 and is entrained about block 71 secured to carriage 13, and about block 72 which may be anchored to the spar tree 26. Likewise haul back line 69 is secured to the carriage 17 and is entrained about block 73 secured to the tail carriage 14 and block 74 which may be anchored to the spar tree 28.

It is obvious that upon winding up of the drum 68 the carriage 17 will be moved toward the lead carriage 13 while upon winding up of the drum 70 and unwinding of drum 68 the hoist carriage will move toward the tail carriage 14. Thus the operator of the yarder 12 by proper manipulation of the winding drums may move either or both of the carriages 13 and 14 in either direction, may move the hoist carriage 17 back and forth between the lead and tail carriages 13 and 14, may lift the hoist carriage 17 by manipulation of the drums 61 and 62, or may perform any of these operations simultaneously. In practice the operator of the yarder operates

the winding drums in accordance with telephone signals from a second operator stationed near the cars being loaded, so that the hoist carriage may be caused to lift a log 5 from any point within the area and deposit it upon a car.

In Figs. 3 to 6 inclusive there is shown a novel form of yarder which is particularly adapted for use with the system described above. The engine 76, winding drums and other working parts of the yarder are mounted upon a suitable frame 77 which is normally supported by a plurality of wheeled trucks 78. The frame 77 is preferably provided with depending side members 79 which extend down within a short distance from the railroad ties 80 of the railroad track upon which the device is adapted to travel. The king pin connection 81 between the trunks 20 and the frame is constructed so as to permit a certain amount of relative vertical movement between the trucks and the frame whereby the trucks may be dropped from the frame to permit the frame to rest upon the ties 80. A convenient way to drop the trucks is illustrated in Fig. 4 in which the rails 82 of the track are shown as provided with cut away portions 83 spaced the proper distance apart to engage the wheels 84 of 25 the trucks. Normally these cut away portions are provided with filler blocks or shims 85. When it is desired to fix the position of the yarder these shims are removed after the wheels have each been positioned adjacent a cut away portion. A slight movement 30 of the trucks then serves to run the wheels down into the cut away portions, thus permitting the trucks to drop away from the frame and the frame to rest directly upon the ties 80. Normally the only portion of 35 the track which is provided with cut away portions is the short spur 22 upon which the yarder is normally side tracked. If desired shims or blocks 86 may be placed under the depending portions 79 before dropping the 40 wheels into the cut away portions in order to insure a level foundation for the frame 77. When it is desired to move the yarder to another point it is only necessary to connect a locomotive to the frame and pull the 45 same in one direction until the wheels of the truck ride upon the tops of the rails after which the blocks 85 are reinserted.

The particular yarder shown has been constructed from a standard four drum donkey which is provided with a forward extension for accommodating the extra drums required. Thus the frame 77 is constructed in two parts and as shown in Fig. 3 the side beams 50 79 are each constructed of two lengths 87 and 88 which are joined upon a rearwardly inclined bias as indicated at 89. This bias junction tends to prevent buckling of the combined frame by tension on the cables.

A novel form of lead carriage for use with

the system of this invention is shown in Figs. 7 and 8, the carriage including a frame comprising a pair of spaced plates 91 between which are journaled sheaves 93 and 94 for engaging the tracking cables 30 and 31.

To prevent undue friction between the cables and the side plates 91 additional rollers 95 and 96 may be mounted upon the side plates adjacent the sheaves 93 and 94 to engage the upper and lower sides of the tracking cables. 70 To maintain the tracking cables in engagement with the sheaves 93 and 94 a plurality of small rollers 97 and 98 are journaled between the side plates 91 and positioned so as to engage the sides of the tracking cables 80 opposite from the sides engaged by sheaves 93 and 94. The two blocks 64 are preferably secured to the ends of a cross beam 99 so that they may be positioned one above the other. These blocks are of conventional 85 construction, each comprising merely a frame 100 within which is journaled the sheave 101. Between the beam 99 and the carriage frame there is a plate 102, preferably of triangular construction which is pivotally connected to 90 the adjacent end of the carriage frame and to the central portion of the beam 99 as by means of clevis connections 103 and 104.

In order to stabilize movement of the cross beam 99 when unequal loads are placed upon the blocks 64, a stabilizer bar 105 is fixed to the member 102 and has its ends connected to the cross beam 99 as by means of links 106. The function for the stabilizer bar 105 is to shift the effective pivotal axis of the cross beam 99 with respect to the carrier frame when unequal cable strains are placed upon the blocks 64. Thus if a heavy pull is placed upon one of the blocks 64 while a light pull is placed upon the other, the beam 99 will not take a position parallel to the side plates 91 but will assume an intermediate angular position since angular movement of the stabilizer bar 105 tends to decrease the distance between the beam 99 and the carriage frame, 100 thereby tending to tension the hoist line 60. The block 71 for the main haul line 67 has been shown as connected to the carriage by means of a yoke connection 107 engaging the central portion of the cross beam 99, and a 105 cable 108. The blocks 44 and 47 for the moving lines 39 and 40 are shown as connected to the plate 102 by suitable means such as clevis connections 109 and 110. In many instances it is desirable to shift the point of 110 connection for the blocks 44 and 47 in order to distribute the pull upon the carriage frame in such a manner that the frame will maintain a position with the side plates 91 practically horizontal with respect to the ground. 115 Thus the plate 102 has been provided with other apertures 111 to which the clevis connections 109 and 110 may be shifted. Correspondingly the side plates 91 have been provided with a plurality of apertures 112 to 120

125 130

130

130

130

which the clevis connections may be made as desired. To aid in operatively positioning the lead carriage and in order to prevent the moving line 40 from becoming entangled with the other cables, the outer end of the carriage frame may be connected to a block 114 for engagement with the cable 40. This block not only serves to position cable 40 but takes some of the strain from cables 30 and 31 and should cables 30 and 31 break, cable 40 would hold until repairs were made.

The specific form of tail carriage which I prefer to employ is shown in detail in Fig. 9. In this figure the parts identical with the lead carriage have been indicated diagrammatically. The tail carriage is similar to the lead carriage with the exception that the cross beam and stabilizer bar have been eliminated. Thus secured to the carriage frame there is a tail triangle 116 to which is secured the blocks 59 and 56 for the moving lines 52 and 51, and the tail block 63 for the hoist line 60. The block 73 for the haul back line 69 may be secured to the triangle 116 as by means of a cable 117 and a clevis connection 118. Apertures 119 are provided in the triangle for shifting the position of the clevis connection 118.

A novel arrangement which may be employed for anchoring the cable blocks is shown in Fig. 10. For example, a representative cable block 120 is shown as connected to an anchoring plate 121. A cable 122 connected to this plate and to a stump or a tree 123 serves to carry the majority of the tension placed upon the block 120 while a cable connection 124 to a tree adjacent the anchoring plate serves to steady the block 120 and at the same time to keep it spaced a certain distance above the ground.

I claim:

1. In a system of the class described, a traversing carriage comprising a frame, a sheave journaled within said frame for tracking the same on a cable, a triangle pivotally secured to one end of said frame, and blocks secured to the corners of said triangle.

2. A lead block comprising a frame, a beam having its intermediate portion pivotally secured to said frame, a member forming a link in the pivotal connection between the beam and frame, a cross bar fixed to said member, connections between the cross bar and the beam at points spaced on either side of the pivotal connection of the beam, and sheaves carried by the ends of the beam.

3. A lead block comprising a frame, a beam secured to one end of the frame, sheaves carried by the ends of the beam, a member inserted between and pivotally secured at its ends to the beam and frame, a cross bar fixed to said member, and connections between the cross bar and beam.

4. A lead carriage comprising a frame having at least one tracking sheave, a beam

pivotally secured to said frame at only one point thereof, sheaves carried by said beam, and means for stabilizing pivotal movement of the beam.

5. In a logging system, a yarder having a plurality of winding drums, horizontally spaced tracking cables, a pair of traversing carriages movably engaging the tracking cables, a hoist cable engaging said carriages and spanning a given area, a hoist carriage associated with said hoist cable, means for raising and lowering said hoist carriage, means for shifting said hoist carriage horizontally, haul cables for effecting movement of said traversing carriages, each of said haul cables extending from a winding drum on said yarder, about a sheave on an anchored block, then engaging a sheave on one of said carriages, about a sheave on a second anchored block, back to a second sheave on the carriage and thence to a point remote from the carriage.

6. In a logging system, a yarder having a plurality of winding drums, horizontally spaced tracking cables, a pair of traversing carriages movably engaging the tracking cables, haul cables for effecting movement of said carriages along said tracking cables, each of said haul cables extending from a winding drum on said yarder, about a sheave on an anchored block, then engaging a sheave on one of said carriages, about a sheave on a second anchored block, back to a second sheave on the carriage and thence to a point remote from the carriage.

7. In a logging system, a yarder having a plurality of winding drums, horizontally spaced tracking cables, a pair of traversing carriages engaging the tracking cables, haul cables for effecting movement of said traversing carriages, one of said carriages being a lead carriage comprising a frame having a tracking sheave, a beam pivotally secured to said frame, sheaves carried by said beam and means for stabilizing the movement of said beam, a hoist carriage, and a hoist cable for controlling said hoist carriage engaging the sheaves in said beam.

In testimony whereof, I have hereunto set my hand.

DAVENPORT LAWSON.
